UNITED STATES PATENT OFFICE

LAZARUS SHAPIRO, OF BRONX, NEW YORK, ASSIGNOR TO RADIO CORPORATION OF AMERICA, A CORPORATION OF DELAWARE

SOUND-REPRODUCING MACHINE

Application filed April 13, 1923. Serial No. 631,764.

This invention relates to sound-reproducing apparatus, and an object of the invention is to produce improved apparatus of the type which will reproduce sound under the control of a plurality of separately actuated devices.

To this end, an important feature of the invention resides in the provision of a sound box and a plurality of separately actuated devices for operating the sound box. Preferably and in the illustrated embodiment of the invention, the sound box is provided with a single diaphragm, and the devices for operating the diaphragm are designed to act alternatively and comprise, on the one hand, means of an electromagnetic character adapted for control by radio receiving apparatus, and, on the other hand, a stylus for operating the diaphragm under the control of a phonograph record.

Another important feature of the invention contemplates the provision of a pivoted, tubular arm having means mounted thereon for reproducing sound under the control of a phonograph record and having other means mounted thereon for reproducing sound under the control of radio receiving apparatus, both of said means being preferably carried by a sound box arranged for movement relatively to the tubular arm.

A further feature of the invention resides in the provision of a sound box mounted to swing forwardly and rearwardly on a pivoted, tubular arm, and having a stylus for operating the diaphragm of the sound box in its forward position relatively to the tubular arm and electromagnetic means for operating the diaphragm of the sound box in its rearward position relatively to the arm.

The bore of the tubular arm may communicate with the horn of the sound reproducing machine in a manner common in the construction of phonographs, and a joint is provided between the sound box and the tubular arm so constructed as to cause communication between the sound box and the tubular arm in both the forward and rearward positions of the sound box relative to the arm.

In accordance with a still further feature

of the invention, the machine is provided with a casing containing means for supporting and rotating a phonograph record and a cover in which radio receiving apparatus is mounted, the sound box of the machine having diaphragm operating means mounted thereon including electromagnetic means and a stylus for actuation under the control of a phonograph record, and connections being provided between the electromagnetic means on the sound box and the radio receiving apparatus in the cover of the machine casing so as to enable the sound box to be operated either by a phonograph record or in accordance with signals received by the radio receiving apparatus.

Still other objects and features of the invention will appear as the description proceeds, and will be pointed out in the appended claims.

In the drawings in which like reference numerals designate like parts throughout the various views:

Fig. 1 is a view in front elevation of a machine embodying the invention, parts of the machine being broken away and the cover being in raised position;

Fig. 2 is a view in sectional elevation taken substantially along the line 2-2 of Fig. 1;

Fig. 3 is a sectional view in plan of the tubular arm and the joint between the tubular arm and the sound box;

Fig. 4 is a view in sectional elevation taken substantially along the line 4-4 of Fig. 3;

Fig. 5 is a diagrammatic representation of the diaphragm of the sound box and the devices for operating it;

Fig. 6 is a plan view of the sound box;

Fig. 7 is a view of the sound box in horizontal section.

Fig. 8 illustrates the permanent magnet carried by the sound box.

Fig. 9 illustrates the base plate of the sound box.

Fig. 10 is a detail view of the coil frame of the electromagnetic means for operating the diaphragm of the sound box; and

Fig. 11 is a view of the coil frame looking toward the left in Fig. 10.

The illustrated machine comprises a casing 2 having a cover 4 hinged thereto as indicated at 6. The casing 2 may be made in a manner usual in the construction of phonographs and has a top plate 7 provided with a removable section 8 on which is rotatably journaled a table 10 operated by a spring motor contained in a housing 12 secured to the under side of the section 8. The casing 2 is further provided with a horn 14, extension 16 and front swing doors 18, such parts being also of a construction and arrangement heretofore employed in phonographs. The horn 14, as shown, has its rear end turned upwardly and secured to the top plate 7. Journaled on the upper side of the top plate 7 is a tapered, tubular arm 20 designed to support separately actuated devices for reproducing sound, one of such devices, as shown, including a stylus 21, operable to reproduce sound under the control of a phonograph record mounted on the rotatable table 10. The journaling of the tubular arm 20 on the top plate 7 enables the stylus 21 to follow the groove of a record mounted on the table 10 in the manner usual in the operation of phonographs.

Preferably and in the illustrated construction, the separately actuated sound reproducing devices for transmitting sound to the bore of the tubular arm 20 are comprised within a single sound box 22, which in turn is provided with a single diaphragm 24 (Fig. 7) and is connected to the tubular arm 20 by a joint including a bowed tube 26 having one of its ends sleeved into a cylindrical member 28 mounted on the free, reduced end 27 of the arm. The end of the tube 26 within the cylindrical member 28 is provided with an opening 30 arranged in alignment with the bore of the tubular arm 20. The other end of the bowed tube 26 has fitted therein a hollow boss 32 projecting centrally from the base of the sound box 22, and is provided with a suitable pin (not shown) arranged to enter a groove 34 (Fig. 6) on the periphery of the boss 32 to enable the sound box to be detachably connected with the bowed tube 26.

As shown (Fig. 7), the sound box 22 comprises a disc 36 formed to provide a chamber 38 on the side opposite from the hollow boss 32. The diaphragm 24 of the sound box is housed within the chamber 38 of the disc 36, and interposed between the edge of the diaphragm 24 and the body of the disc 36 is a ring 42 composed of suitable flexible material. A similar ring 44 is arranged on the opposite side of the diaphragm. The diaphragm 24 and rings 42 and 44 are secured in position within the chamber 38 of the disc by an annulus 46 threaded into the chamber 38. Secured to the disc 36 in any suitable manner is a plate 48 which may con-

veniently be formed from sheet metal, and on the outer face of which is mounted a permanent magnet 50 of generally semi-circular form and having reduced portions 52 and 54 at its ends upon which are mounted oppositely disposed pole-pieces 56 and 58. The pole-pieces 56 and 58 are generally U-shaped in cross section (Fig. 7) and provide a chamber for the reception of a coil frame including spaced sides 60 having correspondingly shaped openings which receive the ends of a rectangular member 62, which, in turn, is adapted to receive an armature 63 for operation by the pole-pieces 56 and 58 of the magnet 50. At opposite sides of 80 the rectangular member 62 are pieces 64, which like the sides 60 of the coil frame, may be composed of brass or other suitable material, and which extend between the sides 60 of the coil frame and through the openings in said sides between the side walls of the rectangular member 62 and the ends of the openings. The pieces 64 are formed at their ends with lugs 66 turned away from the member 62 at right angles to the bodies 90 of the pieces and lying along the outer faces of the sides 60 of the coil frame.

The armature 63 is, preferably and as shown, supported from pieces 64 by means of projections 68 formed integrally with 95 the armature 63 and extending outwardly from the edges 70 of the armature through openings 72 in the side walls of the rectangular member 62. The side walls of the rectangular member 62, which may be made 100 from card-board or other suitable non-conducting material, are preferably quite thin, and the edges 70 of the armature 63 are preferably arranged in close proximity to the sides of said member. Accordingly, if the 105 projections 68 were simply extended outwardly from the edges 70 of the armature, such projections would be relatively short and would not flex readily. In order to cause the projections 68 on the armature 63 to be made readily flexible so as to enable the armature to pivot freely upon such projections, the armature 63 is notched on opposite sides of the projections 68, as indicated at 74 (Fig. 10).

The space defined by the sides 60 and the rectangular member 62 of the coil frame, on the one hand, and by the top of the pole-piece 56 and the bottom of the pole-piece 58, on the other, is occupied by a coil 76, through which an electric current may be passed which will give rise to magnetic flux in the armature and thereby cause the armature to be turned in one direction or the other 125 upon the pivoted projections 68.

As shown, the armature 63 is provided at its opposite ends with ears 78 and 80, the former of which, in the illustrated construction, receives one end of the bar portion 81.

of a T-shaped member 82, and the latter of which receives the free end of a leaf spring 84 carried by the pole-piece 56. The other end of the bar portion 81 of the T-shaped member 82 is connected to the center of the diaphragm 24 as indicated at 86. The leg portion 88 of the T-shaped member 82 extends through a notch 90 in the permanent magnet 50 and is fulcrumed at 92 on a lug 94 extending laterally from the periphery of the disc 36 of the sound box. The stylus or needle 21, hereinbefore mentioned, is mounted in the free outer end of the leg 88. As shown, the permanent magnet 50, pole-pieces 56 and 58, and the coil frame are housed in a cylindrical shell 98 of suitable dimensions.

It will be apparent from the foregoing that the above-mentioned construction includes a stylus 21 by which the diaphragm 24 may be operated under the control of a phonograph record, and that the permanent magnet 50, pole-pieces 56 and 58, and the parts associated with them provide separately actuated electromagnetic means by which the diaphragm 24 may be operated. Although the illustrated construction comprises a single sound box 22 and diaphragm 24 mounted on the tubular arm 20, it is recognized that the arm 20 may be provided with a plurality of sound boxes or with a single sound box having a plurality of diaphragms so long as the sound boxes or diaphragms are operated by separately actuated means.

Preferably and in the illustrated machine, the electromagnetic means, which includes the armature 63 and the parts associated with it, is energized by radio receiving apparatus, and, as shown, the radio receiving apparatus is mounted on a panel 100 supported in the cover 4 of the machine casing. The radio receiving apparatus comprises an inductance coil 102, a coupling coil 104 and a variable condenser 106 contained within a shield 108 (Fig. 2), and further comprises vacuum tubes 110 and transformers 112. The controlling elements of the radio receiving apparatus are mounted on the front of the panel 100 (Fig. 1) and include a main switch 114, a device 116 for adjusting the inductances of the primary and secondary circuits, a device 118 for varying the coupling between the primary and the secondary circuits, and devices 120 and 122 for regulating the variable condensers in the primary and secondary circuits respectively. The radio receiving apparatus does not require to be further described herein, since it may be and preferably is, arranged as described in the application for Letters Patent of Alfred N. Goldsmith, Serial No. 587,067, filed Sept. 9, 1922, for Sound reproducing machine. It is recognized that the electro-magnet having the armature 63 may be ener-

gized by means other than radio receiving apparatus, e. g. by current conducted exclusively over wires, within the scope of certain features of the invention.

In the use of the machine, the diaphragm 24 of the sound box 22 is designed to be operated by the stylus 21 when the sound box is swung forwardly on the tubular arm 20 in position to cause the stylus to engage a record on the table 10, and the diaphragm 24 is designed to be operated by the armature 63 of the electromagnet when the sound box 22 is swung rearwardly with relation to the tubular arm 20, as shown in Fig. 2. It follows, therefore, that the stylus 21 and the electromagnet are designed to operate the diaphragm 24 alternatively. The sound box may be retained in the position shown in Fig. 2 by a stop 124 (Fig. 3) as is usual in phonographs of certain types. In order to permit sound arising from the operation of the diaphragm 24 to be transmitted to the bore of the tubular arm 20, whether the diaphragm is operated by the stylus 21 or by the armature 63 of the electromagnet, the opening 30 of the bowed tube 26 is elongated in the direction of rotation of the tube (Fig. 4) so as to cause the interior of the bowed tube 26 to communicate with the bore of the tubular arm 20 both in the forward position 95 of the sound box relatively to the tubular arm 20 and in the rearward position of the sound box relatively to the arm.

The wires leading to and from the radio-receiving apparatus mounted on the cover 4 of the machine casing 2 are preferably secured to binding posts on a block 126 depending from the top plate 7 of the casing, and the radio receiving apparatus is connected to the electromagnet in the sound box 22 by a wire 128 attached to binding posts on the block 126 and passing into the bore of the tubular arm 20 and from thence through the opening 30 and the bowed tube 26 to the sound box 22. As shown, (Fig. 3) 110 the wire 128 is led outwardly from the bowed tube 26 adjacent to the sound box through a sealed opening 130 and then through a notch 132 in the shell 98 into the sound box. The arrangement of the wire 128 in the manner just described enables the diaphragm of the sound box 22 to be operated at the will of the user either under the control of a phonograph record or in accordance with signals received by the radio receiving apparatus, and at the same time causes the tubular arm 20 and the sound box to present substantially the same outward appearance as in a phonograph in which the diaphragm can be operated only by a stylus.

Having described my invention, what I claim is:

1. A sound-reproducing apparatus comprising a pivoted, tubular arm, a sound box mounted to swing about an axis other than 130

its own forwardly and rearwardly on the arm, and having acoustic connection with the interior of the arm in both the forwardly and rearwardly swung positions, a diaphragm mounted on the sound box, a stylus 5 for operating the diaphragm in the forward position of the sound box relatively to the arm, and electromagnetic means carried by the sound box for operating the diaphragm of the sound box in its rearward position 10 relative to the arm.

2. A sound-reproducing apparatus comprising a sound box, a tubular arm for supporting the sound box, a joint between the 15 sound box and said arm including a tubular member journalled rotatably on the arm and having an elongated slot extending in the direction of rotation of the tubular member so as to cause the sound box to communicate 20 with the interior of the tubular arm in either of two positions of the sound box, a diaphragm mounted on the sound box, a stylus for operating the diaphragm in one of said two positions of the sound box, electromagnetic 25 means for operating the diaphragm in the other of said positions of the sound box, and a conductor housed in said tubular arm and connected to said electromagnetic means.

3. A sound-reproducing apparatus comprising a sound box, a diaphragm mounted on the sound box, a tubular arm for supporting the sound box, a joint between the sound box and the tubular arm including a tubular 35 member communicating with the interior of the sound box and sleeved in said arm, said tubular member having an elongated slot extending in the direction of rotation of the member and being of a length such as to cause the tubular member to communicate 40 with the interior of the tubular arm both when the sound box is swung forwardly with respect to the arm and when the sound box is swung rearwardly with respect to the arm, a stylus mounted on the sound box in position 45 for engagement with a phonograph record when the sound box is swung forwardly on the arm, electromagnetic means carried by the sound box for operating the dia- 50 phragm when the sound box is swung rearwardly with relation to the tubular arm with the stylus out of engagement with a phonograph record, and a conductor extending through said tubular arm and said slot and 55 connected with the electromagnetic means.

4. A sound-reproducing apparatus comprising a sound box, a diaphragm mounted on the sound box, a tubular arm for supporting the sound box, a joint between the sound box and the tubular arm, constructed to provide 60 communication between the diaphragm of the sound box and the interior of the tubular arm both when the sound box is swung about an axis other than its own forwardly with respect to the arm and when 65

the sound box is swung about an axis other than its own rearwardly with respect to its arm, a stylus mounted on the sound box in position for engagement with a phonograph record when the sound box is swung forwardly on the arm, and electromagnetic means carried by the sound box for operating the diaphragm when the sound box is swung rearwardly with relation to the tubular arm with the stylus out of engagement 70 with a phonograph record.
